UNITED STATES PATENT OFFICE.

WALTER C. MEEKER, OF JERSEY CITY, NEW JERSEY.

RAILWAY-FROG.

SPECIFICATION forming part of Letters Patent No. 411,867, dated October 1, 1889.

Application filed April 22, 1889. Serial No. 308,118. (No model.)

To all whom it may concern:

Be it known that I, WALTER C. MEEKER, a citizen of the United States, residing at Jersey City, Hudson county, New Jersey, have 5 invented certain new and useful Improvements in Railway-Frogs, of which the following is a specification.

My invention relates to that class of railroad-frogs commonly known as "spring-rail" 10 or "main-line" frogs; and it consists of the novel construction and combination of parts hereinafter fully described and shown.

As is well known, the object of a spring-rail frog is to give practically an unbroken 15 track for the main line, and this is accomplished by having one of the wing-rails of the frog movable and lying close against the point of the frog and held in position by means of a spring. In order to allow the 20 said wing-rail to lie closely to the point of the frog, it has heretofore been necessary to remove that portion of the flange of said wing on the side next the point. The removal of said flange necessarily weakens the 25 said wing-rail, and thus frequently causes them to break. This breakage of the wings has been the serious objection to the use of 30 spring-rail frogs; but the frog herein described is provided with a spring-rail, which lies close against the point of the frog, but none of the flange is removed. Hence the 35 normal strength of the rail remains and the liability of breakage is obviated. I attain this by the peculiar construction illustrated 40 in the accompanying drawings, in which—

Figure 1 is a perspective view of a frog as 45 constructed in accordance with my invention with a bed-plate. Fig. 2 is a perspective view of the inner side of the spring-rail, showing flange turned up. Fig. 3 is a cross-section taken on the line $x-x$ of Fig. 1. Fig. 4 is a side view of the outer side of the spring-rail, showing more distinctly the offset.

Similar letters refer to similar parts throughout the several views.

A are the rails forming the point of the frog. B is the stationary wing-rail. These parts are riveted to a bed-plate D in the form of construction shown in the drawings, Fig. 50 1, although they may be held together in any other suitable manner and the bed-plate dispensed with.

C is the movable or spring rail.

E E E are raising-plates.

The point-rails A and stationary wing-rail 55 B are constructed in general in the usual manner of forming a frog. The movable or spring wing-rail C is, however, constructed in a novel manner. That portion which lies against the point of the frog is reduced in 60 height, as at d, by compressing the web or neck, so as to form an offset e in the base or flange at least equal to the thickness of the flange of the point. Then the flange next the point is turned or rolled upward, so that 65 it shall not project or extend beyond the line of the head, as shown at c in Fig. 3, thus allowing the head of the said spring-rail to lie closely against the point, and at the same time maintaining the normal strength of the 70 rail. The raising-plates are in thickness equal to the reduction in height of the spring-rail, thus forming a true and firm bearing for the spring-rail.

Longitudinal and upward movements of 75 the spring-rail may be prevented by any of the various means employed in other styles of the spring-rail frogs.

Having thus described my invention, what I claim, and desire to secure by Letters Patent, 80 is—

1. In a railroad-frog, the combination, with the frog-point, of a wing-rail having a portion of one of its flanges turned up to lie against the rail-web, adapting its head to lie 85 against the point of the frog, substantially as described.

2. In a railroad-frog, a wing-rail reduced in height where it lies adjacent to the point of the frog and with its inner flange turned upward, so that the head of said wing-rail may lie against the point of the frog, substantially 90 as described.

3. In a railroad-frog, the combination, with the frog-point, of the stationary wing-rail, the 95 movable wing-rail with the offset on its underside and upwardly-turned flange, and the raising plate or plates, substantially as described.

In testimony whereof I have signed my name to this specification in the presence of two subscribing witnesses.

WALTER C. MEEKER.
